UNITED STATES PATENT OFFICE.

EDWARD F. BARBER, OF IONIA, MICHIGAN.

BOILER ATTACHMENT.

SPECIFICATION forming part of Letters Patent No. 350,099, dated October 5, 1886.

Application filed January 28, 1886. Serial No. 190,117. (No model.)

To all whom it may concern:

Be it known that I, EDWARD F. BARBER, a citizen of the United States, residing at Ionia city, in the State of Michigan, have invented 5 a certain new and useful Boiler Attachment for Warming Ash-Pans and Extinguishing Fire in Ash-Pans on Locomotives or Engines; and I do hereby declare that the following is a full, clear, and exact description of the invention, 10 which will enable skilled mechanics to make and use the same.

My invention relates to devices for throwing water or steam, or both, into the ash-pan of a boiler for the purpose of thawing out the 15 ashes therein, and for the further purpose of extinguishing what fire there might be in the ash-pan after dumping the grate.

In the drawings, Figure 1 is an end view of 20 a boiler with my improved attachment; Fig. 2, a side view, partly in section; and Fig. 3, an enlarged sectional view of the valve or controlling device.

At any suitable point near the top of the 25 boiler K is inserted a double or two-way cock or valve, A, which is provided with steam-passage a, water-passage b, and chamber c. The valve is further provided with valve-plugs B C, by which the supply of steam and water to the chamber c is controlled.

30 A pipe, J, screwed into the lower end or neck of valve A, communicates with the passage b, and extends down into the water in the boiler, as shown in Fig. 2, while a pipe, D, communicates with the chamber c and extends down along the end of the boiler, as shown in 35 Figs. 1 and 2. Pipe D extends down to the bottom of the ash-pan F, near one side, and is carried along one wall thereof, on the inner side, as shown in Figs. 1 and 2, the pipe being perforated along one face within the ash-pan. A second pipe, E, communicates with 40 pipe D above the ash-pan, and extends along the inner face of the latter on the side opposite to pipe D, this pipe E being also perforated within the ash-pan.

45 H indicates the slatted bottom of the ash-pan; I, arms connected thereto, and L the lever for dumping the ash-pan bottom.

M indicates the lever by which the grate is shaken; but inasmuch as these features form 50 no part of the present invention they need not be described in detail.

When the ashes become frozen hard and caked in the ash-pan, it is impossible to dump them, and hence it is desirable to throw steam 55 upon the ashes to thaw them out. This is done by simply closing passage b and opening passage a, whereupon the steam passes through a into c and through pipes D E into the ash-pan, where it is discharged from said pipes, 60 as shown in Fig. 1, the pipes on the opposite sides discharging toward each other entirely across the ash-pan.

When it is desired to discharge water into the ash-pan for the purpose of cooling the hot 65 coals, the passage a is closed and passage b is opened. The steam pressing upon the water forces the same up through pipe J, through 70 passage b, chamber c, and into pipe D, from which it is discharged the same as the steam. By opening both valves B C steam and water will both be forced into and through pipe D and discharged into the ash-pan.

What I therefore claim as my invention, and desire to secure by Letters Patent, is— 75

1. In combination with a boiler and an ash-pan therefor, a two-way valve, A, communicating with the steam-space and the water-space of the boiler, and a pipe connected to 80 said valve and extending into the ash-pan, whereby either steam or water, or both, may be discharged into the ash-pan at will.

2. In combination with boiler K and ash-pan F, a valve, A, communicating with the steam-space of the boiler, a pipe, D, connected 85 to valve A and extending into the ash pan, a pipe, J, connected to valve A and communicating with the water space of the boiler, and valve-plugs B C, for controlling the discharge of steam and water, substantially as shown.

EDWARD F. BARBER.
